UNITED STATES PATENT OFFICE.

JOHN B. DAVIS, OF SPRINGFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS.

LIQUID-DISPENSING APPARATUS.

Application filed January 12, 1927. Serial No. 160,743.

This invention relates to improvements in liquid dispensing apparatus, adapted particularly for the dispensing of gasoline, oils and the like.

5 The invention is directed primarily to the provision of an improved apparatus for the purpose described which apparatus is of the so-called visible measuring type. It embodies a measuring receptacle, preferably 10 transparent, and a gage tube which is movable in the receptacle and measures off the quantities of liquid which are to be dispensed therefrom. Such gage tube, as herein contemplated, is part of the means through 15 which liquid is discharged from the receptacle and preferably consists of a section in the discharge piping which is mounted for vertical sliding movement. The general type of apparatus, just set 20 forth, is old and well known in the art and the present invention is directed to improvements by which the fundamentally old type of apparatus is rendered more suitable and satisfactory for present day needs.

25 Among the general objects are to provide in an improved way for the control of the operations of filling, discharging and draining the measuring receptacle; to provide improved means whereby neither the filling nor 30 the draining operation can take place during the discharge operation; to provide improved means for preventing discharge from the receptacle and insuring the draining of the receptacle when the pump is locked up 35 at night; to provide improved means for registering the quantities of liquid discharged from the receptacle; to provide improved means for preventing tampering with or improper operation of the apparatus; and 40 to provide a generally improved apparatus of the stated type.

There are many details contributing to the accomplishment of the general objects just set forth and these together with other objects and advantages will appear from the following description and be particularly pointed out in the appended claims.

45 The invention will be disclosed with reference to the accompanying drawings, in which:

Fig. 1 is a small scale exterior elevational view of an apparatus embodying the invention;

Fig. 2 is a fragmentary elevational view,

drawn to a larger scale, and showing the 55 door of the casing open and showing also such parts of the operating mechanism as are accessible when the door is opened;

Fig. 3 is a sectional plan view taken on the line 3—3 of Fig. 1;

Fig. 4 is a central sectional elevation of the apparatus looking from the same direction as in Fig. 1;

Fig. 5 is a fragmentary cross sectional view of the apparatus taken at right angles 65 to Fig. 4 and drawn to a somewhat larger scale;

Fig. 6 is a front elevational view of that section of the apparatus shown in Fig. 2, but drawn to a larger scale and with the casing 70 and shields removed so as to show the interior mechanism;

Figs. 7 and 8 are end elevational views of that portion of the apparatus shown in Fig. 6 and are taken, respectively, from the left, 75 hand and right hand sides of Fig. 6;

Figs. 9 and 10 are sectional plan views taken on the lines 9—9 and 10—10 of Fig. 5;

Fig. 11 is a fragmentary front elevational view, taken similarly to Fig. 6 but with parts 80 of the channel-iron panel broken away to clearly show parts therebehind;

Fig. 12 is a sectional plan view taken on the line 12—12 of Fig. 11;

Fig. 13 is a view of the supply valve with 85 parts broken away to show the interior;

Fig. 14 is a sectional view showing the detail of the adjustable mounting of the register-operating pins; and

Fig. 15 is a detail view, partly in section, 90 of the latch for the sliding discharge pipe.

The dispensing apparatus includes a suitable measuring receptacle, such as the glass cylinder 20 (Figs. 1 and 3), the lower end of which is closed by a base 21 and the 95 upper end of which carries a cap 22. The base and cap are drawn together by bolts 22' so as to clamp the cylinder 20 therebetween. The cap 22 is provided with a suitable air venting device 23 and serves to support a suitable dome 24. The cylinder 20 may be graduated in any suitable manner and, as shown in Figs. 1, 3 and 5, is graduated in gallons by one or more sets of 100 appropriate level markers 25, each set comprising a vertical series of markers mounted on a rod 26 which is secured to and extends 105 between the base and cap members. With

in the receptacle are located supply and overflow pipes 27 and 28, respectively, both being tapped into base 21 (Fig. 3) and extending upwardly therefrom and terminating near the upper end of the receptacle. The supply pipe 27, which is preferably capped by a suitable deflector 29 to direct the incoming liquid downwardly, terminates at a higher level than the overflow pipe 28. The receptacle is provided with a movable gage tube, in the shape of a discharge pipe 30 which is slidable through a suitable stuffing box 31 in base 21 and extends through the latter and into a pipe 32 secured to and depending from the base. Pipe 32 forms one branch of a U-shaped well, the other branch consisting of a parallel pipe 33 which is connected at its lower end by a return bend fitting 34 to the lower end of pipe 32 and extends upwardly, in parallel relation therewith, terminating with an outlet pipe 35. The latter customarily is supplied with a discharge valve, which is indicated at 36 in Fig. 1 and is adapted for connection to a flexible dispensing hose, indicated at 37. To avoid siphoning of the contents of said well, a vent tube 38 (Fig. 4) is provided to connect the top of pipe 35 to the upper part of cylinder 20, such tube communicating through cap 22 with the cylinder at a point well above the contemplated maximum level of liquid therein and thus with the air space thereof.

The receptacle 20 is supported by a pedestal, herein shown as a hollow, frusto-conical sheet metal casing 39, which is secured at its upper end to the base 21 of the receptacle and at its lower end to a supporting base 40 (Fig. 4). Casing 39 is provided with an opening 41 (Figs. 2 and 5) through which convenient access may be had to such parts of the apparatus as are necessary to reach for the normal operation of the apparatus. The casing 39 serves not only to conceal but to render inaccessible all other parts including those which if accessible, might be improperly or fraudulently manipulated. The opening 41 can be closed by a door 42 (Figs. 1 and 2), which is hinged along one side to the casing and on the other side is slotted so that when closed it fits over a hasp 43 (Fig. 1) adapted to receive a padlock such as 44, whereby the apparatus may be locked up when desired, as when not in use. The casing 39 (Figs. 1 and 2) is provided with a recess 44 (for a purpose to be later described) which is formed in the lower side of the door opening 41 and extends downwardly below the bottom edge of the door.

Liquid may be supplied to receptacle 20 through its supply pipe 27 by any suitable means and examples of various suitable means will be found in the prior art. For illustrative purposes, a pump 45 of the re-

ciprocating piston type, is shown in Fig. 4 in more or less conventional form. Such pump is housed within the lower part of pedestal 39 and is supported from base 40 by a series of posts 46. The pump may be operated in any suitable way, as for example, manually by a lever 47, located outside casing 39 and mounted on a shaft 48, which is rotatably mounted, as indicated, in bearings provided on the pump casing. Shaft 48 has fixed thereto, at a point inside casing 39, a lever 49 which is connected by links 50 to the piston rod 51 of the pump, whereby the pump piston may be reciprocated in an obvious manner. Pump 45 has an inlet pipe 52, which is adapted for connection to a liquid supply tank (usually located underground), and an outlet pipe 53, which extends vertically upwards in a straight line, and in axial alignment with the receptacle supply pipe 27. Pipe 53 is tapped into base 21 and its upper end is at all times in communication with pipe 27. Intermediate its ends, pipe 53 is provided with a supply valve 54, by means of which communication between pump 45 and receptacle supply pipe 27 can be closed off, when desired. Valve 54 may be of any suitable type and, as shown, is of the type having a horizontally disposed stem 54' which is turned back and forth to effect an opening and closing of the valve. As illustrated, valve 54 is open and if its stem is turned clockwise, as viewed in Fig. 4, through an angle of approximately 45 degrees from the position there shown, the valve will be closed. The means for operating the supply valve will be later described.

The means for returning from the measuring receptacle such liquid as is not delivered to the customer comprises a pipe 55, which is tapped into base 21 and always in full communication with the receptacle overflow pipe 28, and a drain pipe 56 which is also tapped into base 21 and communicates with the receptacle so as to be capable of drawing off all liquid therein down to the level of the lower end of the glass cylinder 20. Both pipes 55 and 56 extend vertically downward from base 21 in spaced parallel relation and at their lower ends are connected to a manifold 57, to which is also connected a pipe 58 adapted for connection to, or communication with, a suitable receiver, usually but not necessarily, the underground supply tank above referred to. The drain pipe 56 has interposed between its ends a drain valve 59, which is normally closed but can be manually opened, when required, by means to be later described to drain the measuring receptacle. The drain valve 59 may be of any suitable type and, as shown, has a vertically disposed stem 60 which is adapted to be turned back and forth through a small angle to effect an opening

or closing of the valve. As illustrated, the drain valve is closed but if its stem be turned clockwise, as viewed in Fig. 10, from the position there shown, the valve will be opened.

The sliding discharge pipe 30 is adapted to be manually moved up and down. When positioned as shown in Fig. 4 it lies in what is hereinafter called "Fill" position and the upper end of pipe 30 lies high enough above the upper end of overflow pipe 28 so no liquid can enter it during any normal operation of the apparatus. The deflector 29 directs the pumped liquid away from the open end of pipe 30. This pipe 30, which is located coaxially with respect to the measuring receptacle, is adapted to be moved from "Fill" position vertically downward to, and held in, a plurality of positions in each of which it is effective to discharge a predetermined measured quantity, viz, that volume of liquid contained in the receptacle between the top of the overflow pipe 28 and the top of the discharge pipe 30. The latter is adapted to be moved by a handle 61 by which a vertical rod 62 may be moved. Such rod passes vertically upwards through a suitable stuffing box in base 21 (Fig. 5) and into the measuring receptacle, being disposed directly in front of discharge pipe 30. This rod 62 at its upper end is fixed by a clamp 63 (Fig. 3) to the upper end of the discharge pipe 30. The rod 62 is fixed at its lower end to a hub 64 (Figs. 5, 9, 11 and 12) having a pair of forwardly projecting and laterally spaced ears 70 and between which an arm 65 of rectangular cross section is fixed. Such arm 65 projects forwardly and the handle 61 is pivoted to the outer end thereof at 66, so that the weight of the handle tends to move it into a position at right angles to and depending from the arm. Such is the position of handle 61 necessary to permit closing of door 42. In normal operation, handle 61 is lifted until it lies horizontally and in continuation of arm 65 and it may be fixed in this position by a removable pin 67 which passes through the arm and handle at a point in back of the pivot pin 66.

Means are provided for guiding the rod 62 in its reciprocating movement. Such means include a vertically disposed member 68 (Figs. 6, 9 and 10), herein shown as made of sheet metal and having a channel-like cross section,—the legs of the channel extending rearwardly. This member, which is roughly coextensive in area with and located just in back of the door opening 41 (see Fig. 2), serves to conceal and render inaccessible such parts of the apparatus as are not necessary to reach in normal operation. The member 68 at its upper end is secured by cap screws 69 (Figs. 6 and 7) to two laterally spaced ears 70 which as best

shown in Figs. 4 and 9, project forwardly from a clamp member 71,—the latter and a companion member 72 encircling the centrally located pipe 32 and being clamped thereto by bolts as indicated. The operating rod 62 passes freely between the spaced ears 70 as shown in Figs. 9 and 11. The lower end of member 68 is similarly secured to the front member 73 of a two part clamp (Figs. 8 and 10), which encompasses, and is bound to, the overflow pipe 55 at a point just above the manifold 57. The member 68 is provided with a centrally located, vertically extending slot 74, through which the rectangular arm 65 projects (Figs. 5 and 6) and in which it is guided. The ends of slot 74 are closed and the length of the slot is such as to admit of the desired extent of vertical travel of discharge pipe 30. In back of channel member 68 is a rod 75, having its axis disposed in parallel relation with that of the discharge pipe. This rod 75 is fixed at its ends, the lower end being received in clamp 73 (Figs. 5 and 10), and the upper end in one of the ears 70 of front clamp 71 (Figs. 5 and 11). The hub 64, at the base of the discharge pipe operating rod 62, carries a laterally projecting ear 76 (Figs. 11 and 12) which encircles and is slidingly engaged with rod 75, to function as a further guide for the discharge pipe.

In order to hold the latter in various predetermined vertical positions, a series of quantity stops are provided, any one of which may be swung into the path of the arm 65 to limit its downward movement. As best shown in Fig. 6, there are nine such stops, designated 77 and mounted end to end in abutting relation on a common rod 78. Each stop 77 is free to turn on rod 78 throughout an angle of about 180 degrees (see also Fig. 9) from a position wherein it presents no obstruction to the passage of arm 65 to a position in which it crosses slot 74 and is adapted to arrest arm 65 when it is lowered. Each stop is provided with an adjustable part 79 with which arm 65 engages,—such part 79 being adjustable and commonly sealable for the usual reasons.

A spring 80 is mounted in a recess in each stop 77, as illustrated in connection with the upper stop, and adapted to create a friction on rod 78, tending to hold the stop in the positions to which it may be moved. The rod 78 is mounted at its ends in upper and lower bearings 81 and 82 which are secured to channel 68. Conveniently, the upper bearing 81 is provided with a bushing 83 which is used as a means of holding the quantity stops against axial movement. The bushing is driven down in bearing 81 until it abuts the upper stop 77 and until the several stops have been moved into abutting relation. A pin 84 is then passed through the bearing, bushing and rod to preserve the ad-

- justment. The nine stops 77 may be consecutively marked from "1" to "9" in a descending scale to indicate gallons or any other suitable quantity. When arm 65 abuts the part 79 of a stop 78, say that marked "5" for example, the upper end of discharge pipe 30 will be lowered below the upper end of overflow pipe 28 just far enough so that five gallons of liquid can be drawn from receptacle 20 through the discharge pipe. When arm 65 is engaged with other stops of the series, other measured quantities corresponding to the numbers on the stops, can be similarly delivered. For the tenth gallon, or other unit quantity, a fixed stop 84 (Fig. 4) is mounted on the back of channel 68 and extends across slot 74 to define the extreme lower limit of travel of arm 65 in slot 74.
- Means are also provided for registering the quantities of liquid discharged from the measuring receptacle through discharge pipe 30. Such means takes the form of a counter or cumulative register 85, (shown in Figs. 6, 7 and 9) which is or may be of the Veeder type and operated by certain movements of the sliding discharge pipe. Inasmuch as the register is of a well known type, detailed description is not required.
- It will suffice to say that, when its operating shaft 86 is turned in a counter-clockwise direction, as viewed in Fig. 8, the register will be operated and, when this shaft is turned in the opposite direction, the register will not be operated. Shaft 86 has fixed to its other end a five pointed star wheel 87 and the latter, when turned one fifth of a revolution in a counter-clockwise direction, will operate register 85 and register one unit.
- The register is fixed to an arm 88 (Fig. 9), secured to the hub 64, whereby the register is bodily moved when the discharge pipe 30 is moved. The star wheel, as shown in Fig. 8, moves in a path adjacent and along one side of channel 68 and projecting into this path are a series of pins 89 which are adjustably fixed as indicated in Figs. 8 to 14, to said side face of the channel in longitudinally spaced relation. There are ten of such pins, one for each of the quantity stops. One pin 89 is located opposite each of the movable stops, and the tenth pin is located at a point above the uppermost stop 77. In lowering the discharge pipe, these pins 89 serve to successively turn the star wheel 87 in a clockwise direction so that register 85 is not operated. On the upward movement of pipe 30, the star wheel is successively turned by the pins 89 in the proper direction to operate the register and as arm 65 passes by one quantity stop after another, each such increment of upward movement is counted on the register 85.
- It is to be noted that, if the pipe 30 is lowered, even slightly, below any one of the
- movable quantity stops the counter will be so operated as to register a quantity corresponding to that designated by the next quantity stop therebelow. Say, for example, the arm 64 is carried below the nine gallon stop but not to the ten gallon stop, then a point of the star wheel is brought into position below the lowermost of the pins 89 so as to be operated thereby on the return stroke of arm 65. On such stroke ten gallons will be registered even though only nine and a fraction were dispensed. The quantities are in a sense registered in advance so that the pipe 30 cannot be manipulated without registering at least all that is discharged. That more than the quantity discharged may be registered in cases where arm 30 is positioned between the stops is an insurance against the operator cheating the owner of the apparatus. The operator is supposed always to move arm 30 into abutment with some one stop and if he does so the correct quantity is registered. If he does not do so, then more is registered than is dispensed and, as the proprietor uses this register to check the honesty of his employee, the latter will be held accountable for the extra quantity registered but not dispensed. Consequently, this provision tends to force the employee to set the discharge pipe in the proper and contemplated manner.
- An extra pin 90, called the eleventh pin, is provided on channel 68 at the upper end of the path of movement of the register. This pin 90 merely insures that the star wheel is properly positioned at the end of each dispensing operation so as to function properly on a succeeding operation. Pin 90 forces one point of the star (the forwardly projecting one) to lie exactly horizontal as shown in Fig. 8, when the meter is moved to the upper limit of its stroke, in the event that it is not already so positioned. Pin 90 does not cause the registration of an additional unit quantity and it is provided as the usual safe-guard necessary to proper operation of the register.
- Before the receptacle 20 can be filled, arm 65 must be raised into "Fill" position. When so positioned, register 85 lies directly in back of a window 91, so that the unit quantities registered on the preceding movement of the discharge pipe can be ascertained. The register supporting arm 88 is, of course, provided with an opening so that the face of the register will be visible through the window 91 under the conditions described.
- As an additional guide for the discharge pipe and particularly as a means for preventing deflection of the register in a direction such that the center of star wheel shaft 86 might move nearer to or farther away from its actuating pins 89, an arm 92 integral with, but longer than arm 88 is pro-

vided (see Fig. 9). Such arm rides in a guiding slot 93 (Fig. 8) formed between the vertically disposed side edges of two plates 94, which are secured at their lower ends to the clamp member 73 (see also Fig. 10). At their upper ends, they are secured to an angle iron 95 fixed to clamp 71 (Fig. 9).

In order to hold the discharge pipe in "Fill" position a spring latch 96 (best shown in Fig. 6) is bevelled on its lower face and projects across slot 74. This latch is slidably mounted in a body 97 fixed to channel 68, for movement in a direction transverse to slot 74. It is urged to the position shown by a spring 98 (Fig. 15) and can be manually retracted by a finger piece 99 integral therewith. In raising the discharge pipe 30 into "Fill" position arm 65 engages the lower face of latch 96 and acts on it like a cam, forcing it to the left (as viewed in Fig. 6) so that arm 65 can pass. As soon as arm 65 has passed, spring 98 returns the latch into illustrated position, whereby arm 65 is supported and holds pipe 30 in "Fill" position. After the filling operation has taken place and it is desired to lower pipe 30, latch 96 must be manually withdrawn and this may be conveniently effected by finger piece 99.

Referring back to the filling operation, the supply valve 54 is interconnected with the sliding discharge pipe 30 so that it cannot be opened while pipe 30 occupies any position in which it is effective to discharge liquid. This valve can only be opened when pipe 30 is raised to its uppermost or "Fill" position. The movement of pipe 30 into said position is made to automatically open valve 54 and on movement of the pipe out of said position and towards the first of its discharge positions, valve 54 automatically closes. To secure these results the following mechanism is used. A segment plate 100 is fixed to the stem 54' of valve 54 (Figs. 4, 5 and 10) and perforated (Fig. 4) to receive the right angularly turned lower end of a rod 101, (Figs. 7 and 10), which extends upwardly and is loosely guided in a hole in a plate 102, as best shown in Fig. 11, which plate is secured to one of the ears 70 of clamp member 71. Fixed to rod 101 at a point below plate 102 is an arm 103, the outer end of which is forked to straddle the fixed guide rod 75 (Fig. 12). The ear 76, which moves with discharge pipe 30 and slides on rod 75, engages arm 103 as the pipe 30 approaches the upper limit of its travel, and lifts this arm into the illustrated position thereby raising rod 101, whereby segment 100 is turned in the proper direction to open valve 54. As pipe 30 is moved downwardly out of "Fill" position and ear 76 moves away from arm 103, a spring 104 moves rod 101 downwardly until valve 54

is fully closed. Spring 104 encircles rod 101 and acts between plate 102 and arm 103. A sleeve 105 encompasses spring 104 and is used as a stop to positively limit the degree of rotation of the stem of the supply valve. This is desirable here because the valve is operated by an eccentric (see Fig. 13) and if turned too far in the described direction to open the valve might result in a closing of the valve, particularly where, as here, the pressure of the pumped liquid tends to close the valve. No stop is necessary for the downward movement of rod 101 as the latter is checked by the engagement of the valve with its seat, as will be apparent from Fig. 13.

The drain valve 59, as above described, has to be manually opened and, unless positively held open, it will automatically close. The drain valve operating handle is designated 106 and is shown in Figs. 1 and 2 in the positions which it occupies when the door 42 is closed and open, respectively. Handle 106 is fixed to a slide 107, (as best shown in Figs. 6 and 7), slidably mounted on that side face of channel 68 opposite from the register operating pins 89. The handle normally projects forwardly through door opening 41, as shown by full lines in Fig. 7, in such a way that door 42 cannot be closed. When, however, handle 106 is lowered into recess 44, as shown by dotted lines in Fig. 7, the door is free to close and, when the door is closed, it functions to hold handle 106 from rising far enough to cause a closing of the drain valve. The slide 107 is provided with vertical slots 108 (Fig. 7) and is secured to channel 68 by bolts 109 which pass through such slots. Thus slide 107 is free to slide within the limits set up by the confines of slots 108. Slide 107 has a rearwardly projecting part 110 (Fig. 7) perforated to receive the right angularly turned lower end of a vertical rod 111, which passes through and is guided in a bracket 112 secured to channel 68. A spring 113 acting between guide 112 and a washer 114, which is held in place as shown by a cotter pin, tends to move slide 107 upwardly and yieldingly holds it in the illustrated position. The lug 110 has a right angularly turned and laterally projecting ear 115 (Figs. 6, 7 and 10) which is slotted to receive a pin 116 fixed to an approximately horizontally disposed arm, designated 117, of a bell crank lever. The latter is pivoted intermediate its ends at 118 to an arm 119 (Figs. 7 and 10), which is integral with and projects at right angles from one end of a clamp member 120. The latter and its companion clamp member 121 encircle the supply pipe 53 and are held thereto as indicated in Figs. 7 and 10. The other arm of the bell crank lever, designated 122, extends approximately vertically upwards and its upper end is bent forwardly there-

from to form an ear 123 (Figs. 6 and 7). The latter underlies a segment plate 124 which is fixed to the vertical stem 60 of drain valve 59, as indicated in Fig. 10. A pin 125 is fixed to ear 123 and is received in a substantially radial slot in segment 124. By pushing down on handle 106, slide 107 is lowered, carrying with it ear 115, which, by means of pin 116, rocks arm 117 of the bell crank lever. Thus, the other arm 122 of such lever is moved and by means of pin 125 causes the segment 124 and attached stem 60 to turn in the proper direction to open the drain valve. Spring 113 operates to move the parts in a reverse manner to close the drain valve and tends at all times to close such valve.

Means are provided, whereby the discharge pipe 30, if positioned in "Fill" position, cannot be lowered from such position into any discharge position while drain valve 59 is open. Such means consists of a plate 126 which is fixed to and projects forwardly from a slide 127 (Fig. 7). This slide is similar to the lower slide 107 and is similarly mounted above the latter. The upper end of the described rod 111 is right angularly turned and received in a perforation in plate 126. By means of the described rod 111, the upper slide 127 is caused to move in unison with the lower slide 107. Thus, when the drain valve is opened plate 126 will be lowered from the illustrated position and when this plate is so lowered, it presents an obstruction to the finger piece 99 of latch 96, (as will be apparent from Fig. 6), whereby the latter cannot be moved sufficiently to allow arm 65, and thus discharge pipe 30, to be moved downwardly from "Fill" position.

In the event that the discharge pipe has already been moved into some discharge position, it is necessary to then prevent opening of the drain valve. This result is very simply accomplished by means of an arcuate abutment 128 which is fixed to the back of the supply valve operating segment 100 and in concentric relation with the stem of the supply valve. When the discharge pipe is in "Fill" position, segment 100 has been turned in a counter-clockwise direction into the illustrated position and the abutment 128 has thereby been raised high enough to allow free passage (to the left as viewed in Fig. 6) of the drain valve segment 124. Thus, the drain valve can then be opened. However, when pipe 30 is lowered from such position, the segment 100 is turned clockwise and abutment 128 is moved into the path which segment 124 has to take to cause an opening of the drain valve. The arcuate extent of abutment 128 is such as to prevent the described movement of the drain valve segment in any position of the discharge pipe 30 except the one "Fill" position there-

of. As above described, pipe 30 cannot be moved out of "Fill" position until the drain valve is closed and as soon as pipe 30 is moved from such position opening of the drain valve is prevented. Thus, improper manipulation of the drain valve is effectually guarded against.

As a still further precaution, however, an indicator, herein shown in the shape of one or more arrows 129, is provided to apprise the customer of whether the apparatus is set to deliver the liquid to his car or to the storage tank. Preferably, a pair of arrows (as indicated in Fig. 3) are used and they project outside the casing 39 and are disposed in the plain view of the purchaser (Fig. 1). These arrows play over opposite faces of a plate 130 which is appropriately marked on said faces with upper and lower legends as for example "To storage" and "To car". The arrows, which are pivoted on a common axis to plate 130 (Fig. 4), normally point to the lower legends, viz, "To car". However, the opening of drain valve 59 is made to cause the arrows to swing upwardly and point to the legends "To storage", as shown in Fig. 1, whereby the customer can easily ascertain, if he uses ordinary precaution, when the drain valve is open. To operate the arrows 129 they are connected by a single link 131 (Fig. 4) to the approximately horizontal arm 132, of a bell crank lever which is pivoted intermediate its ends at 133 to a collar 134, fixed to the overflow pipe 55. The other, and approximately vertically depending arm, of the bell crank lever, designated 135, has at its lower end a forwardly projecting and right angularly turned ear 136 (Fig. 8). This ear overlies the drain valve operating segment 124 and is slotted to receive a pin 137 which is fixed to and upstands from the segment. Thus, when the latter is moved, the arrows are moved and the arrows thus indicate whether the drain valve is open or closed.

The channel 68 forms a panel and it is approximately coextensive in area with the door opening 41 and is located directly in back of the door. The parts, to which access is required when door 42 is opened, are located in front of the panel, such as the handles 61 and 106 and the several quantity stops 77. All other parts are located behind the front face of the panel and are, for the most part, concealed thereby. Fig. 2 shows the arrangement clearly. This panel constitutes part of what may be termed a shielding means, which is designed to render inaccessible through door opening 41 all parts of the mechanism except such as require access for the normal operation. To supplement the panel 68, and insure the result described, plates 139 (Figs. 2 and 10) are provided which are secured to the front

face of the panel, one along each side edge thereof, and extend outwardly and in opposite directions therefrom. These plates 139, which complete the shielding means, prevent one from reaching through door opening 41 and gaining access to the slides 107 and 127 together with all other parts of the drain valve operating linkage except the handle 106; the supply valve or any of its operating connections; the register 85 or its star wheel or the operating pins 89 therefor; and the linkage for operating the arrow indicator. In short, only the handle for operating the drain valve, the handle for moving the discharge pipe, the holding latch 96 for the discharge pipe, and the quantity stops 77 can be reached through the door opening. Tampering with the essential parts of the operating mechanism is thereby rendered as inconvenient as possible.

In operation, when the receptacle is filled for the very first time only part of the contents of receptacle 20 will be discharged through hose 37 because part of the liquid drawn from the receptacle through pipe 30 will remain in the U-shaped well. The pipes 32 and 33 and their connecting manifold 34 must first be filled with liquid up to the level of the outlet pipe 35. When the apparatus is first set up, the well is filled to the described level and the register 85 is then set to zero. Thereafter, the apparatus will operate properly in the contemplated manner, delivering correctly measured quantities through the hose 37 and registering such quantities as are thus dispensed.

The normal operation of the apparatus requires, as a prerequisite to the filling of receptacle 20 with liquid, the setting of the discharge pipe 30 in "Fill" position. That is, the upper end of the pipe 30 must be raised to a level high enough above the overflow pipe 28 so that no liquid can enter during the filling operation. The discharge pipe 30 is, of course, empty having been drained down to the level of outlet pipe 35. When the pipe 30 is thus positioned, the supply valve 54 is open, having been opened by the movement of pipe 30 into "Fill" position. The receptacle 20 may then be filled by a few strokes of the pump 45, operated manually by the lever 47. Meanwhile, the drain valve 59 is closed—such valve closing automatically by reason of spring 113 when door 42 was opened and remaining closed thereafter unless manually held open. Opening of the drain valve during the filling of receptacle 20, if attempted, will cause the arrow indicator to point to the legend "To storage" and thus the customer will be warned. In any event, the discharge pipe 30 cannot be lowered while the drain valve 59 is open. It must be closed before liquid

can be delivered to the customer and the latter is supposed to exercise the common precaution of observing that the receptacle 20 is filled to the level of the top of the overflow pipe before the discharge valve 36 is opened. The customer is thus protected if he observes ordinary precautions. None of the pumped liquid can enter the discharge pipe 30 during the filling operation to work a fraud on the owner of the apparatus. As soon as the receptacle has been filled to a level above the upper end of overflow pipe 28, pumping is stopped and the receptacle then drains through pipe 28 down to a predetermined level defined by the upper end of said pipe. Liquid cannot drain back through the supply pipe 27 because its open end lies well above the top of the overflow pipe.

Having receptacle 20 filled with liquid to the predetermined level, the operator then manually releases latch 96 and lowers the discharge pipe. This, as has been said, cannot be done if the drain valve is then open because plate 126 prevents the release of the latch. Immediately, the discharge pipe is lowered, the supply valve is closed. No liquid can therefore, be pumped into the receptacle while pipe 30 is discharging. The operator, having previously moved a quantity stop 77 (corresponding to the desired quantity) into position so as to arrest arm 65, or if the full contents are desired, having first insured that all stops 77 are retracted so as to leave a free passage for arm 65 to the fixed stop 84, the discharge pipe is lowered until arrested by the abutment of arm 65 with the selected stop. By opening valve 36, the receptacle 20 will then drain through pipe 30 down to the level of the upper end of such pipe and the measured quantity between said level and the aforesaid predetermined level will be delivered to the purchaser through hose 37. No diversion of this measured quantity by way of the drain pipe 56 is possible because the drain valve 59 has to be closed before delivery of such quantity can be made and it cannot thereafter be opened while the discharge pipe 30 is in any of its plurality of discharge positions because the lowering movement of pipe 30 causes abutment 128 on segment 100 to be swung into the path which the segment 124 of the drain valve has to take in order to open the latter.

On the down stroke of pipe 30, the star wheel 87 of register 85 is turned step by step as it successively engages pins 89 but such turning is idle and results in no operation of the register. On the up stroke of pipe 30, the pins 89 successively cause the star wheel to be turned step by step in a direction such as to operate the register and by increments such that the one unit is registered by each movement of the star wheel.

The measured quantities are thus registered after they have been discharged. Registration of such quantities is compulsory, however, because the receptacle 20 cannot be again filled until the pipe 30 has been raised to "Fill" position and the raising movement of the pipe causes the registration of at least all of the quantities dispensed. As hereinbefore set forth, more than the quantities dispensed will be registered if the operator positions the pipe 30 between the fixed quantity positions so that the operator, being accountable for the quantities registered by the meter, has no incentive to operate the apparatus in this manner.

In locking up the apparatus at night, the operator is forced to open the drain valve 59 before he can shut and lock door 42. Moreover, he cannot open this valve until he has first set the discharge pipe 30 in "Fill" position. This causes the measured quantity last dispensed by him to be registered. While it also opens the supply valve, the discharge pipe is raised to its upper position so that no liquid can enter it and, if pumping is then attempted, the pumped liquid merely drains back through the open drain valve to storage. It is generally a custom to provide a padlock such as that indicated at *p* in Fig. 1, for locking the pump operating lever 47 to casing 39 so that filling of the receptacle is prevented but the above described provisions are such that no harm can ensue even if the operator neglects to lock the pump lever.

The invention has been disclosed herein, in an embodiment at present preferred, for illustrative purposes, but the scope of the invention is defined by the appended claims rather than by the foregoing description.

What I claim is:

1. In a liquid dispensing apparatus, a measuring receptacle, a supply conduit through which liquid is delivered to the receptacle, a fixed overflow conduit for draining off all liquid in the receptacle above a predetermined level, a discharge pipe having its receiving end mounted for movement in said receptacle and adapted to be positioned at various levels below said predetermined level to discharge liquid from the receptacle and adapted also to be positioned above said predetermined level in a position in which it is ineffective to discharge liquid from the receptacle, a valve in said supply conduit, and means operable by movement of said pipe into the last named position to open said supply valve.

2. In a liquid dispensing apparatus, a measuring receptacle, a supply conduit through which liquid is delivered to the receptacle, a fixed overflow conduit for draining off all liquid in the receptacle above a predetermined level, a discharge pipe having its receiving end mounted for movement

in said receptacle and adapted to be positioned at various levels below said predetermined level to discharge liquid from the receptacle and adapted also to be positioned above said predetermined level in a position in which it is ineffective to discharge liquid from the receptacle, a valve in said supply conduit, and means operable by movement of said pipe into the last named position to open said supply valve and to hold the same open until said pipe is again lowered.

3. In a liquid dispensing apparatus, a measuring receptacle, a discharge pipe movable therein from one position in which it is ineffective to discharge liquid from said receptacle to various other positions in which it is effective for such discharge, draining means for said receptacle including a normally closed controlling valve, and means operable when the discharge pipe is moved from the first named to any of the second named positions to prevent the opening of said valve.

4. In a liquid dispensing apparatus, a measuring receptacle, a discharge pipe movable therein from one position in which it is ineffective to discharge liquid from said receptacle to various other positions in which it is effective for such discharge, draining means for said receptacle including a normally closed controlling valve, means for supplying liquid to said receptacle including a controlling valve, means for opening and closing the supply valve operable by movement of said discharge pipe into and out of said first named position, respectively, and means operable when the discharge pipe is moved from the first named to any of the second named positions to prevent the opening of said drain valve.

5. In a liquid dispensing apparatus, a measuring receptacle, a discharge pipe movable therein from one position in which it is ineffective to discharge liquid from said receptacle to various other positions in which it is effective for such discharge, draining means for said receptacle including a normally closed controlling valve, means for supplying liquid to said receptacle including a controlling valve, means for opening and closing the supply valve operable by movement of said discharge pipe into and out of said first named position, respectively, and means connected with the supply valve and operable as the latter is opened or closed to permit or prevent the opening of the drain valve.

6. In a liquid dispensing apparatus, a measuring receptacle, a discharge pipe movable therein from one position in which it is ineffective to discharge liquid from said receptacle to various other positions in which it is effective for such discharge, draining means for said receptacle including a normally closed controlling valve, and means op-

- erable by the opening of said drain valve and effective when said discharge pipe occupies its first named position to prevent the discharge pipe from being moved out of said 5 position.
7. In a liquid dispensing apparatus, a measuring receptacle, a discharge pipe movable therein from one position in which it is ineffective to discharge liquid from said receptacle to various other positions in which it is effective for such discharge, draining means for said receptacle including a normally closed controlling valve, releasable means for holding said discharge pipe in its 10 first named position, and means effective when the drain valve is open to prevent the release of said last named means.
8. In a liquid dispensing apparatus, a measuring receptacle, a discharge pipe movable therein from one position in which it is ineffective to discharge liquid from said receptacle to various other positions in which it is effective for such discharge, draining means for said receptacle including a normally closed controlling valve, a casing enclosing said draining means and valve and provided with an opening, a lockable door for closing said opening, a handle for opening said drain valve projecting through said 15 opening and preventing the closing of said door when the drain valve is closed and permitting said closing when the drain valve is open, and means whereby said discharge pipe must be moved into said first named position before said drain valve can be opened, whereby when said door is closed it is insured that said receptacle is drained and that no liquid can be drawn from said discharge pipe.
9. In a liquid dispensing apparatus, a measuring receptacle, means for supplying liquid to the latter including a supply conduit and a controlling valve, a discharge pipe movable in the receptacle from one position in which it is ineffective to discharge liquid 20 from the receptacle to various other positions in which such discharge is permitted, means for opening the supply valve by movement of said pipe into the first named position and for closing the supply valve by movement of said pipe out of said position, draining means for the receptacle including a normally closed controlling valve, a casing serving to house said means and valves and provided with an opening, a lockable door adapted to close said opening, a handle for opening the drain valve and interfering with the closing of said door when the drain valve is closed, said handle when moved to open the drain valve permitting the closing of said door, and means whereby said discharge pipe must be moved to said first named position before said drain valve can be opened, whereby when the door is closed it is insured that said receptacle is drained and that liquid cannot be drawn from said 25 discharge pipe notwithstanding that said supply valve is open.
10. In a liquid dispensing apparatus, a measuring receptacle, a discharge pipe movable in the receptacle from one position in which it is ineffective to discharge liquid from the receptacle to various other positions in which such discharge is permitted, means for supplying liquid to said receptacle operable only when said discharge pipe is in said first named position, draining means for the receptacle including a normally closed controlling valve, a casing serving to house said means and valves and provided with an opening, a lockable door adapted to close said opening, a handle for opening the drain valve and interfering with the closing of said door when the drain valve is closed, said handle when moved to open the drain valve permitting the closing of said door, and means whereby said discharge pipe must be moved to said first named position before said drain valve can be opened, whereby when the door is closed it is insured that said receptacle is drained and that liquid cannot be drawn from said discharge pipe notwithstanding that said supply means may be operative.
11. In a liquid dispensing apparatus, a measuring receptacle, a discharge pipe movable therein from one position in which it is ineffective to discharge liquid from said receptacle to various other positions in which it is effective for such discharge, draining means for said receptacle including a self closing controlling valve, a casing housing said means and valve and provided with an opening, a door for closing said opening, a handle for opening said drain valve and interfering when the latter is closed with the closing of said door, a recess in the casing communicating with the door opening into which recess the handle is lodged when moved to open the drain valve, said door when closed serving to hold said handle in said recess and thus the drain valve open, and means whereby the discharge pipe must be moved into the first named position before the drain valve can be opened.
12. In a liquid dispensing apparatus, a measuring receptacle, a discharge pipe mounted for vertical sliding movement therein, means reciprocable in a straight line path for raising and lowering said pipe, a cumulative register carried by and movable with said means, and stationary means adjacent the path of travel of said register for actuating the latter on movement of said pipe.
13. In a liquid dispensing apparatus, a measuring receptacle, a discharge pipe mounted for vertical sliding movement therein, means reciprocable in a straight line path for raising and lowering said pipe, a cumulative register carried by and mov-

able with said means, and stationary means adjacent the path of travel of said register for actuating the latter during the raising movement only of said pipe.

- 14. In a liquid dispensing apparatus, a measuring receptacle, a discharge pipe mounted for vertical sliding movement therein, means reciprocable in a straight line path for raising and lowering said pipe, a cumulative register carried by and movable with said means, a stationary panel having a vertical slot, said reciprocable means including a handle and a part connected to the latter and guided in said slot, and a series of vertically spaced pins carried by said panel for actuating said register by movement of said pipe.
- 15. In a liquid dispensing apparatus, a measuring receptacle, a discharge pipe mounted for vertical sliding movement therein, means reciprocable in a straight line path for raising and lowering said pipe, a cumulative register carried by and movable with said means, a stationary panel having a vertical slot, said reciprocable means including a handle and a part connected to the latter and guided in said slot, and a series of vertically spaced pins carried by said panel for actuating said register during the upward movement only of said pipe.
- 16. In a liquid dispensing apparatus, a measuring receptacle, a hollow supporting pedestal therefor provided with an opening, a door for closing the latter, a sliding discharge pipe in said receptacle, a vertically movable member accessible through said opening for moving said pipe, a series of stops accessible through said opening and selectively movable into position to hold the discharge pipe in various positions of vertical adjustment, and shielding means for closing off access through said opening to all parts of said hollow interior behind said member and stops.
- 17. In a liquid dispensing apparatus, a measuring receptacle, a hollow supporting pedestal therefor provided with an opening, a door for closing said opening, shielding means including a panel located directly in back of said opening and having its forward face accessible when said door is open, said panel provided with a vertical slot, supply

and drain pipe connections to said receptacle including a controlling valve for each, a discharge pipe mounted for movement in said receptacle, operating connections for moving said pipe including a part projecting through said slot and provided with a handle, a plurality of devices independently operable from the front face of said panel, any one of said devices adapted to be moved into the path of said part to support the discharge pipe in various positions of vertical adjustment, means for operating the supply valve by movement of the discharge pipe, a handle for operating the drain valve accessible through said opening, said shielding means serving to prevent access to said supply and drain valves and the operating connections therefor except said drain valve handle and also to the operating connections for said discharge pipe except for its operating handle.

18. In a liquid dispensing apparatus, a measuring receptacle, a discharge pipe movable therein, a vertically reciprocable member connected to move said pipe, a panel member adjacent to and parallel with the path of travel of said reciprocable member and provided with a vertical guide slot, an operating arm on said reciprocable member projecting transversely therefrom and through said slot, and a series of quantity stops mounted on said panel member for independent movement into and out of the path of said arm.

19. In a liquid dispensing apparatus, a measuring receptacle, a discharge pipe movable therein, a vertically reciprocable member connected to move said pipe, a panel member adjacent to and parallel with the path of travel of said reciprocable member and provided with a vertical guide slot, an operating arm on said reciprocable member projecting transversely therefrom and through said slot, and a series of quantity stops pivotally mounted on said panel member for independent swinging movement about a vertical axis, each of said stops adapted to be swung from an inactive position to a position in which it crosses said slot and lies in the path of said arm.

In testimony whereof I have affixed my signature.

JOHN B. DAVIS.
